Patented Apr. 26, 1921.

Oscar Wm Trilsch ^{INVENTOR}

UNITED STATES PATENT OFFICE.

OSCAR WM. TRILSCH, OF WHITESTONE, NEW YORK.

DESIGN FOR A DISPLAY-BOX FOR BEAD NECKLACES.

57,747.

Specification for Design.

Patented Apr. 26, 1921.

Application filed March 20, 1919. Serial No. 283,940. Term of patent 7 years.

To all whom it may concern:

Be it known that I, OSCAR WM. TRILSCH, a citizen of the United States, and resident of Whitestone, L. I., in the county of Queens and State of New York, have invented a certain new, original, and ornamental Design for a Display-Box for Bead Necklaces, of which the following is a specification.

Referring to the drawing, the figure is a

perspective view of a display box for bead necklaces showing my new design.

I claim:

The ornamental design for a display box for bead necklaces, as shown.

Signed at Whitestone L. I., in the county of Queens and State of New York, this 13th day of March, A. D. 1919.

OSCAR WM. TRILSCH.
